UNITED STATES PATENT OFFICE.

DAVID A. JONES, OF SPRINGFIELD, MASSACHUSETTS.

COMBINED TWEEZERS, WATCH-KEY, &c.

Specification forming part of Letters Patent No. **77,621**, dated May 5, 1868; antedated April 22, 1868.

To all whom it may concern:

Be it known that I, DAVID A. JONES, of Springfield, Hampden county, Commonwealth of Massachusetts, have invented a new and useful Improved Combination of Tweezers, Ear-Spoon, and Watch-Key; and I do hereby that the following is a full and exact description thereof, reference being had to the accompanying drawings, and to the letters of reference marked thereon.

In the drawings, Figures 1, 2, &c., are plan and side views of my invention.

This invention consists of a combined arrangement of tweezers, watch-key, and ear-spoon, whereby they are compactly and neatly put together, and can be used separately, as far as their respective uses are concerned, by merely shifting the parts to the proper positions.

In construction I form my tweezers of two slotted pieces, A and A', which have the ends *a* formed with clear and corresponding edges, making the nippers, the other ends being fastened on each side of a piece, B, by means of a rivet, *c*, through them. The plates A and A' are cut out in the middle, leaving a tongue, *d* and *d'*, on each of them, extending from toward the rivet *c*, this forming a spring-lock for the piece B when turned either way. The piece B has a longer and shorter end, *f* and *g*,

the one *f* having the ear-spoon at its end, and having its shank grooved on each side, into which grooves *h* the projections *i i'* upon the ends of the tongues *d d'* clamp when the end *f* is turned in, and the other end, *g*, which is the watch-key, is set out. When this is reversed the projections *i i'* upon the tongues meet in front of the slot in the watch-key and prevent dirt and trash from getting into it. In this case the lock is formed by the underneath surfaces of the tongues being hollowed out so as to conform to the cylindrical shape of the key-shaft.

In this manner I obtain a neat and useful device which can be carried in the pocket or attached to the watch-guard. It is very light, and at the same time sufficiently strong for the operations intended to be accomplished.

Having described my invention, what I claim as new, and desire to secure by Letters Patent, is—

The combination of the tweezers A A', ear-spoon *f*, and watch-key *g*, arranged and constructed substantially as and for the purpose shown.

DAVID A. JONES.
